UNITED STATES PATENT OFFICE.

NELSON A. MICHAELSON, OF UNIONTOWN, PENNSYLVANIA.

MINE CAGE.

Application filed November 12, 1921. Serial No. 514,623.

To all whom it may concern:

Be it known that I, NELSON A. MICHAELSON, a citizen of the United States, and resident of Uniontown, in the county of Fayette 5 and State of Pennsylvania, have invented certain new and useful Improvements in Mine Cages, of which the following is a specification.

This invention relates broadly to self-dumping mine cages in which, when hoisted to the top of the mine shaft in which they are erected, the mine cages are automatically caused to tilt or dump in order to discharge materials loaded in mine cars positioned on the cage platforms into a chute which conveys the material to other suitable cars, and more particularly relates to an apron adapted to prevent spilling of the materials from the cars on the cages into the mine shaft 15 while said cages are being tilted.

The principal object of this invention is to provide an apron of the class set forth above that will be entirely automatic in operation.

25 Referring to the drawings, forming a part of this specification, Figure 1 is a top plan view of a mine cage and conveying chute having my invention applied thereto.

Figure 2 is a sectional elevation on the 30 line II—II of Figure 1, showing the apron in its retracted position.

Figure 3 is a similar view showing the apron in its projected or operative position.

In the drawings, the letter A designates 35 the self-tilting mine cage as a whole, which may be of any well known construction, and is shown composed of side members or posts 2, between which is supported a platform 3 having rails 4 thereon and having slots or 40 recesses 5 therein for the wheels 6 of the mine cars 7. The ends of the mine cars 7 are provided with hinged doors 8 adapted to swing outwardly to open position, to allow the discharge of the material carried in said cars 45 when the cage A is tilted. The tilting mechanism of the mine cage is not shown, since it does not form part of this invention.

An inclined channel-shaped chute B is mounted adjacent the mine shaft and is supported on a girder 9 extending between posts or upright supports 9^a by suitable brackets or angle braces 10. The chute B is so arranged with relation to the mine shaft, that when the cage A is tilted it will receive the 55 material discharged from the car 7 carried by said cage.

The chute B comprises a bottom portion 11, side members 12, and stiffening angles 13 and 14 secured across the bottom and sides respectively. 60

The above cage and chute construction is well known in the art, and therefore will not be described further in detail.

In order to prevent spilling of smaller particles of material that, with little or no 65 velocity, will dribble from the car as the cage is being tilted, from falling down the mine shaft or between the chute B and cage A, I provide an apron C. The apron C comprises a flat plate 15 mounted within the 70 chute B and having a longitudinal angle stiffening member 16 secured on the under side along the rear edge thereof, and transverse angle members 17 secured on the upper face along each end thereof. 75

A pair of supporting brackets 18 are secured to the side members 12 of the chute adjacent their top edges, and links 19 are pivotally secured to said brackets and to the forward ends of said angle iron members 17 80 so as to suspend the forward end of the apron plate above the bottom of the chute.

A pair of crank arms or levers 20 are pivotally secured to the supporting brackets 18, and have their lower ends pivotally secured 85 to the rear ends of the angle-iron member 17 to suspend the rear end of the apron plate above the bottom of the chute, while their upper ends project beyond the chute and into the path of travel of the cage A when tilting, forming an operating portion 21 which is adapted to engage the wear plates 22 on the cage as the cage tilts. 90

The operation of the invention is as follows— 95

As the cage A is tilted to discharge the contents of the car 7, the cage will engage the operating portion 21 of the crank levers 20, thus moving or rocking the apron plate 15 rearwardly until it projects beyond the chute B, as shown in Figure 3, forming an extension to receive the smaller particles of material that will dribble, with little or no velocity from the car 7 as the cage is tilted, thereby preventing such particles falling 105 down the mine shaft between the cage A and chute B. Upon the reversal of the cage A, after the car 7 has been emptied and is being lowered into the shaft, the cage will release the portions 21 of the crank levers 20 110 and allow the apron plate 15 to normally move forwardly by gravity, out of the path

of the descending cage. However, if the plate 15 does not move forwardly by gravity, the cage platform will strike the curved portion of the crank levers 20 adjacent their lower ends, and force said levers and the plate 15 to move forwardly and out of the path of the descending cage.

While only one specific embodiment of the invention has been shown and described, it will be understood that I do not wish to be limited to said specific structure, since various modifications may be made without departing from the spirit of my invention as defined in the appended claims.

15 I claim:—

1. The combination with a tilting mine cage, and a chute adapted to receive materials from cars carried by said cage, of an apron member pivotally suspended from the rear end of said chute and adapted to be moved rearwardly by said cage as it is moved into tilting position.

2. The combination with a tilting mine cage, and an inclined channel-shaped chute adapted to receive materials discharged from mine cars carried by said cage when said cage is tilted, of an apron member pivotally suspended from the sides of said chute, and means adapted to be operated by said cage as it is moved into tilting position to move said apron rearwardly, thereby forming an extension of said chute adapted to prevent any of the material discharged from the mine car falling between said chute and said cage.

3. The combination with a tilting mine cage, and an inclined channel-shaped chute adapted to receive materials discharged from mine cars carried by said cage when said cage is tilted, of an apron member mounted on the rear end of said chute and adapted to

be moved rearwardly by said cage as it is moved into tilting position to form an extension of said chute to prevent the material discharged from the mine car falling between said chute and said cage, said apron comprising a flat plate member, angle-iron side members, links pivotally secured adjacent the forward end of each of said angle-iron side members and to the sides of said chute, and crank arms pivotally secured adjacent the rear end of said angle-iron side members and at a point intermediate their ends to the sides of said chute, said crank arms having one end projecting beyond said chute into the path of travel of said cage and adapted to be engaged thereby when tilting.

4. The combination with a tilting mine cage, and an inclined channel-shaped chute adapted to receive material discharged from mine cars carried by said cage when said cage is tilted, of an apron suspended from suitable supports secured to the side walls of said chute, said apron comprising a flat plate member, angle-iron side members secured to said plate member, links pivotally secured to said angle-iron side members adjacent their forward ends and to said supports on said chute, and crank arm operating levers pivotally secured adjacent one end to said angle-iron side members and pivotally secured intermediate their ends to said supports on said chute, said crank arms having a portion thereof projecting beyond said chute and into the path of travel of said cage, so as to be engaged by said cage and operated to move said apron rearwardly when said cage is tilted.

In testimony whereof I have hereunto set my hand.

NELSON A. MICHAELSON.
